UNITED STATES PATENT OFFICE.

THEODORE M. FOOTE, OF NEW YORK, AND FRANK ANDERSON, OF PEEKSKILL, ASSIGNORS TO THE AMERICAN RAPID TELEGRAPH COMPANY, OF NEW YORK, N. Y.

MECHANISM FOR PERFORATING PAPER FOR TELEGRAPHIC PURPOSES.

SPECIFICATION forming part of Letters Patent No. 228,623, dated June 8, 1880.

Application filed May 3, 1879.

To all whom it may concern:

Be it known that we, THEODORE M. FOOTE, of New York city, in the county of New York and State of New York, and FRANK ANDERSON, of Peekskill, in the county of Westchester and State of New York, have invented certain new and useful Improvements in Mechanism for Perforating Paper for Telegraphic Purposes, of which the following is a specification.

10 This invention relates to certain improvements in that class of telegraphic apparatus technically known as "perforators," for perforating paper employed in telegraphy, the perforations in the paper serving to transmit certain impulses of electricity from a transmitting 15 to a receiving instrument upon or over a circuit of conductors.

Heretofore perforators have been so constructed that the perforations formed by the same represent certain character-alphabets—such as the Morse, for instance—the spacing or feeding of the paper between the perforations depending upon the length of the character or perforation representing the character.

25 This invention, although it relates in some of its parts to perforators of the class above mentioned, is specially applicable to the perforation of paper metricaly or by measurement, the perforation representing a letter consisting simply of a single hole for single-current transmission and two holes for double-current or polarity transmission, the spacing or distance between the perforations being in relation to certain letters which they represent, and corresponding in distance between the same to the distance between such letters.

The invention is specially designed to be employed in connection with the system of telegraphy embraced in United States Letters Patent No. 191,130, dated May 22, 1877, which requires apparatus for perforating, transmitting, receiving, and translating or changing the recorded dots or dashes into Roman letters, and it has specially for its object to provide for the perforating and spacing the paper, so that said perforations and spaces will correspond in arrangement with the letters in the translating or copying machine.

In the translator hereinbefore referred to, and for a full understanding of which reference is made to patent of Theodore M. Foote, No. 191,130, dated May 22, 1877, the letters on the type-wheels are, for convenience, arranged with special reference to each other, the letters most often used being arranged on one wheel, directly opposite those least used, which are upon another wheel. The intermediate wheel is marked with the numerals in common use. The levers to the right and left and opposite the type-pad operate said pad to print from the wheels respectively upon the fillet.

It is the function of the record upon the receiving or record fillet to indicate to the operator which keys are to be depressed, and this indication is given by the last or right-hand dot of each couple. For instance, if the couple of dots stand in this position, $\circ\circ$, the last dot, being in the upper row, shows that one of a certain set of levers is to be depressed and cause a letter of, say, the farthest wheel from the operator to be printed upon the translating fillet. If the dots stand in this position, $\circ\circ$, the last dot, being in the lower row, shows that one of another set of levers is to be depressed and a letter of the nearest wheel printed, while a certain predetermined repetition of dots or couples may indicate that a certain key is to be operated to print from the intermediate wheel.

It is the object of the present invention to rapidly prepare the perforated strips to be used in transmitting messages, the receiving or record strips of which are to be used in connection with the translator, as explained.

It consists, mainly, in the combination, with the punches of a telegraphic perforating-machine organized to perforate a fillet in two rows, of feeding mechanism for varying and regulating the spaces between perforations representing letters in connection with said spaces, and devices for controlling the operation of the punches, so as to reverse the successive perforations as regards their relative positions in the respective rows, so that successive perforations shall be removed a proper distance from those immediately preceding, to

indicate that another letter is to be printed, and that said perforations shall occupy a position to indicate which wheel of the perforator is to be used.

5 In the accompanying drawings, Figure 1 represents a top view of our improved apparatus; Fig. 2, a front elevation with the key-levers detached; Figs. 3 and 4, detached views of the punch-mover; Fig. 5, the perforated fillet of paper; Fig. 6, a sectional view on the line $x-x$ of Fig. 1; Fig. 7, a sectional view on the line $y-y$ of Fig. 1, and Fig. 8 a side elevation of the apparatus.

The letter p indicates a continuously-revolving shaft journaled in suitable supports G , and adapted to be driven by any convenient power. Said shaft has rigidly secured to it a ratchet or spur wheel, T , and has mounted loosely upon it a pulley, O , provided with cams J and P , and a clutch or pawl, S . The letter D indicates a shaft mounted in the supports G and parallel with the shaft p . Said shaft D has rigidly secured to it a pulley, d , drum or cylinder A , and feed-roller E . The shaft D is driven by the pulley O in its revolution through the medium of a loose belt, U , traveling on O and d , when the clutch or pawl S' is made to engage the ratchet T , as more fully herein-after explained.

25 30 The pulley d is constructed of less diameter than the pulley O , so that the cylinder A will make a complete revolution in or about the time the main shaft is making three-fourths of a revolution, or thereabout.

35 40 In lieu of the pulleys and belt, gear-wheels may be substituted, in which event the gear-wheel on the shaft D should have a less number of teeth than the gear-wheel on shaft p , in order to give the proper relative speed to the two shafts, and when such gear-wheels are used the cylinder A should be fitted loosely on shaft D and be driven by suitable friction devices.

The cylinder A is provided with a number 45 of pins, a a a , arranged spirally around its periphery, and in certain relation to each other, as more fully hereinafter specified.

The letter u indicates a roller supported by a lever controlled by a spring, so as to bear 50 against the paper-drum or feed-roller E with a yielding spring-pressure.

The letters M and L indicate two swinging frames, having bearings at m^4 m^5 in a suitable support. The frame M has attached to it a rod, m , extending from an arm, m^2 . The said rod is provided with an upright arm, o , and an arm, o' , which extends at right angles from said rod behind the upright swinging stop t , attached thereto, as shown in Fig. 7 of the 60 drawings.

The letter k indicates a lever attached to a bell-crank lever, K , one end of which bears against the boss of an arm, i , secured to the shaft I . The said shaft I has also attached to 65 it a punch-mover, H .

The letter O represents a series of key-le-

vers extending over and resting upon the frames L and M and pivoted at c . Certain of said key-bars are recessed, as shown at C' , Fig. 7, for the purpose hereinafter explained.

The letter B represents a series of upright stop-bars loosely mounted in a rack-frame, b , and held forward in place by the spring s' , as shown in Fig. 6.

The stop-bar corresponding to each particular key is moved upward when said key is depressed and brought under one of the projections a on the cylinder A , and by the rotation of said cylinder is carried against the stop, arresting the rotation of the cylinder. The 80 said stop-bars fall forward and out of the way of the pins a when a key is released, so that if a letter is to be repeated the cylinder may make another revolution, or as many as may be desired, without its being stopped, by simply depressing and releasing the key.

The letter f indicates the punches, which are supported in a frame, F' , to which is secured a die, a^2 . Motion is imparted to said punches in one direction by a spring, h , and 90 in the opposite direction by the punch-mover when the same is thrown against the punches by the rocking motion of the shaft I , imparted to the same by the cam J , the said cam as it revolves acting against an arm, i , secured to the shaft I . The punch-driver is provided with three apertures, f^2 f^3 f^4 , which permit such punches as may not be required in forming the perforations to remain in a normal position by falling into said apertures while the 100 other punches are being operated.

The punch-mover H has given to it upon the depression of any of the key-levers that bear upon the frame L by the action of the rod k and bell-crank lever K , acting upon the boss of the 105 arm i , (or it may be upon any projection secured to the shaft,) a reciprocating lateral movement, which shifts the position of said punch-mover, serving to actuate a different set of punches, as indicated in Figs. 3 and 4 of the 110 drawings.

The letter X represents the winding-reel, and V the delivery-reel, supported upon suitable bearings in the uprights 10 and 10'. Attached to the support 10 at y is an arm carrying a roller or guide-wheel, Y , which is separated from the roll X a distance equal to the width of the paper to be wound upon said reel in said guide-wheel, serving to hold and guide the paper upon the reel X , which has but one flange. The said guide-roller is capable of a swinging or oscillating movement in the arc of a circle, in order that it may bear constantly upon the paper as the size of the roll increases by the winding of the paper upon the same. The said reel X is provided with a series of pins, 2 2, arranged in a circle at a proper distance from the center, upon which the paper is coiled or wound, by means of which the starting of the paper upon the reel is facilitated and the removal of the roll of paper from the reel is more readily and conveniently 125 130

effected. The reel X is driven by a suitable belt, x, extending from the shaft r, the said belt being arranged to slip upon its bearing when the paper is wound taut, and in order that the momentum of the reel X may not rupture the paper a brake, z, suitably supported, is arranged to be brought against the reel X the instant that the paper is wound taut.

The arm Z is attached to a support, 10, at 3, 10 and carries a pin, z', and roller w³, the pin z' being held away from the edge of the reel X by a suitable spring. An arm, W, is attached to the support 10, and carries a pin, v, and roller w', the pin v bearing upon the periphery 15 of the reel V. The paper passes from the reel V over the roller v and under the roller R on the frame F, and from thence over the feed-roller E and under u over the roller w³ and upon the reel X. In order that the paper may 20 not be broken by the sudden movement of the feed-roll E, the first strain is brought on the lever W at the roller u, permitting the reel to be started easily, and to prevent its running too far the spring 4 causes the pin 2 to 25 act as a brake upon the reel V. By the arrangement of the pulleys O and d and belt U the shaft D makes a complete revolution in less time than the main shaft p, the object being to allow the cylinder A to move to its 30 proper position, and the paper fed or moved the proper distance at the first part of the revolution of the main shaft, the perforation being accomplished at the latter part of the revolution. Upon the cylinder being arrested by 35 the stop-bars B coming in contact with the pins a a a, the belt U will slip on the pulley d, the main shaft completing its full revolution while the cylinder is at rest.

The pins a a a, in conjunction with the stop-bars B and key-levers, serve also to regulate and determine the movement of the paper-feed rollers, and thereby the movement or spacing of the paper, which is of varying lengths, depending upon the relative distance between 45 the keys as expressed by their respective pins, as arranged circumferentially on the cylinder A.

The operation of the machine will be readily understood in connection with the foregoing 50 description.

Motion being imparted to the main shaft p by any suitable power, upon depression of a key, C, bearing on the frames M L, the hooked rod m is drawn forward, throwing the upright t 55 forward from under the bell-crank lever N, when it is thrown down upon the pin p' by the spring n releasing the end of the clutch S, when it is thrown into and upon the spur-wheel T by the spring s. Simultaneously 60 with the movement of m, the rod k is drawn forward, operating the bell-crank lever K, which gives lateral motion to the rod l and the parts attached thereto. Simultaneously therewith the stop-bars B are thrown up into 65 the path of the pins a on the cylinder A.

It will be observed that all of the movements described occur simultaneously, and as

the clutch is connected to the spur-wheel T the pulley O and cam-wheels P and J are revolved with the main shaft p, the belt U on pulley O 70 driving the shaft D, cylinder A, and paper-feed roller E, the pulley d, being of smaller diameter than O, making its complete revolution in less time than the shaft p, so that the paper is moved in the first part of the revolution, 75 while the perforating is effected at the last part, the operations being effected as follows: As the cam-wheel J rotates, the cam thereon trips the lever i, oscillating the punch-mover H, which drives or forces the punches through 80 the punch-head F' into the die a², perforating the paper which passes between the punch-head and the die a², as indicated in Fig. 8 of the drawings.

Upon the key being released the parts assume their normal positions hereinbefore described. Upon the depression of such keys as are provided with the openings c', the movements are the same as before described, excepting that the frame L remains in its normal inactive position and the lateral position of the punch-mover remains unchanged.

Having thus fully described our invention, what we claim as our invention is—

1. The combination, with the punches of a 95 telegraphic perforating-machine organized to perforate a fillet in two rows, of feeding mechanism for varying and regulating the spaces between perforations representing letters, in connection with said spaces, and devices for controlling the operation of the punches, so as to reverse the successive perforations as regards their relative positions in the respective rows, substantially as described, and for the purpose set forth.

2. The combination, with the key-levers and the shaft carrying the paper-feed roller, of the stop-bars B, the friction-cylinder mounted on said shaft, and having the projections for operating said bars, the stop for limiting the 110 rearward movement of said bars and of the cylinder, and motive devices connected with said cylinder and controlled by the key-levers, substantially as described.

3. The continuously revolving shaft and 115 ratchet and the loose pulley and clutch, in combination with the revolving paper-feed-regulating cylinder and connecting belt or suitable gearing, substantially as described.

4. The combination of the key-levers, the 120 main rotary shaft p, carrying the ratchet T, the loose pulley P on said shaft, carrying the clutch S, the intermediate mechanism between the key-levers and the said clutch, the paper-feed mechanism and devices connecting the 125 same with the loose pulley, and the punching devices, also connected with and operated by said pulley, substantially as described.

5. In combination with the key-levers and feed-cylinder, the stop-bars B, arranged to 130 have not only a vertical movement, but also a lateral movement, as and for the purposes set forth.

6. In combination with the paper-feed rollers,

and intermittently-acting punches, the winding-reel and paper-delivery reel, the yielding roller n , and automatic friction-brake W , for preventing the rupture of the paper and undue delivery of the same as it is drawn from said reel, and the yielding roller n^3 and automatic brake-lever z , for regulating the movement of the winding-reel, substantially as described.

In testimony that we claim the foregoing we have hereunto set our hands in the presence of the subscribing witnesses.

THEODORE M. FOOTE.
FRANK ANDERSON.
